CIRCUIT BREAKER

Ernst Speck, Los Angeles, Calif., assignor to
 Zinsco Electrical Products Company, Los Angeles, Calif.

Application November 26, 1948, Serial No. 62,045

3 Claims. (Cl. 200—88)

1

This invention relates generally to circuit making and breaking devices, and more particularly to electric circuit breakers which are automatically operable either thermally or magnetically in response to abnormal current overload.

An object of this invention is to provide a circuit breaker particularly adapted, although not necessarily, for use in performing its protective function in conjunction with a manually operable switch, with the invention being structurally characterized by means which insures a firm and positive physical engagement between the relatively movable contacts of the breaker under heavy spring pressure, so as to reduce electrical resistance at the contacts to a minimum, yet render the circuit breaker extremely sensitive and practically effortless in tripping in response to sustained overloads within a preselected narrow range, whereby to obtain identical and precise overload performance as well as cool operation and quick resetting of the breaker.

Another object of this invention is to provide a circuit breaker which obtains its sensitivity and dependability of operation within the narrow range of current overloads by means of a substantially frictionless latching element introducing a force reducing couple which minimizes stress at the point of latching the circuit breaker in set position, to a negligible amount as compared to the heavy friction loads imposed by heavy contact-engaging springs on trip release devices of circuit breakers heretofore proposed, which cause such breakers to run hot at near rated loads and to be sluggish and undependable in operation.

Another object of this invention is to provide a circuit breaker of the thermal, bi-metal type in which the mechanical force exerted by the bi-metal element in tripping the breaker is greatly reduced, thereby avoiding distortion or "permanent setting" of the bi-metal element and resulting inaccuracies or failure of the breaker operation.

With these and other objects in view, this invention resides in the combinations, arrangements and functional relationships of elements as set forth in the following specification and particularly pointed out in the appended claims.

In the accompanying drawings,

Figure 1 is a view in side elevation, of one form of circuit breaker embodying this invention, with a cover plate removed to show the mechanism of the circuit breaker in set position, and with certain parts in section for the sake of clearness;

2

Figure 2 is a view similar to Figure 1, with the circuit breaker in tripped position;

Figure 3 is a view similar to Figure 1, with the positions of the parts of the mechanism during the act of resetting and immediately prior to latching in set position; and

Figures 4 and 5 are transverse sectional views taken on the lines 4—4 and 5—5, respectively, of Figure 1, and looking in the directions of the respective arrows.

Referring specifically to the drawings, this invention in its illustrated embodiment comprises a hollow base 10 suitably formed of a molded electrical insulating compound and having an open side closed by a cover 11 (Figures 4 and 5) of similar material secured to the base by suitable fastening members 12.

A U-shaped metal bracket 13 is confined in a fixed position in the base 10 by lugs 14, 15 and 16, and is provided with aligned, V-shaped notches 17 in which seat pivot lugs 18 outstruck from the sides of a U-shaped switch or contact arm 19 freely movable between the sides of the bracket 13 and carrying a movable contact 20 adapted to engage a stationary contact 21 secured to a flexible bus contact 22.

A pigtail 23 electrically connects the contact arm 19 with the bracket 13, and a second pigtail 24 connects the bracket with a bi-metallic or thermal trip member 25 secured to a load contact bar 26 having a wire terminal 27 provided with a wire clamping screw 28. From the foregoing, it will be clear that when the contact arm is in the extreme position shown in Figure 1 wherein the movable contact 20 engages the stationary contact 21, that a branch circuit will be closed between the bus contact 22 and the wire terminal 27.

Interposed between the contact arm 19 and the trip member 25 is a mechanism composed of a trigger 30 pivotally mounted at one end in the base 10 by a pin 31 and having connected thereto intermediate its ends, one end of a heavy over-center spring 32, the other end of which is connected to a pin 33 carried by the contact arm 19. Co-acting with the trigger 30 and the trip member 25 is a latch 40 pivotally mounted in the base 10 by a pin 41. The latch 40 is of U-shaped cross section to freely receive the trigger 30 between the sides thereof for engagement of the latching nose or tip 42 of the trigger with the keeper shoulder 43 at one end of the latch adjacent to its pivot pin 41.

At its other end remote from the pivot pin 41, the latch 40 is provided with a latching toe 44

which is engageable by the free end of the flexible arm 45 of the trip member 25 so as to be retained thereby in the set position shown in Figure 1. A coil spring 46 is mounted on the pivot pin 41 and has one leg 47 engaging a cross bar 48 on the latch, and another leg 48 engaging a wall 50 of the base 10 so as to urge the latch 40 to its tripped position shown in Figure 2.

A segmental shaped operating member 55 having a finger piece 56 projecting through a slot 57 in the base 10, is mounted in the latter for oscillating movement about the axis of the pivot lugs 18 by means of arcuate flanges 58 on opposite sides of the member riding in arcuate grooves 59 in the base and in the cover 11. When the circuit breaker occupies its set position shown in Figure 1, movement of the operating member 55 manually in one direction or the other will actuate the contact arm 19 by engagement of one end 60 or the other end 61 of the operating member with the contact arm 19, so as to shift the spring 32 to one side or the other of the axis of the pivot lugs 18.

Thus, the contact arm 19 will be instantly moved to one extreme position wherein the movable contact 20 engages the stationary contact 21 as shown in Figure 1, or another extreme position wherein the movable contact is disengaged from the stationary contact as shown in Figure 2. A ball 65 mounted in a bore 66 in the finger piece 56 is urged by a spring 67 into engagement with the base lug 14 for coaction with cam faces 68 and 69 on the lug, in insuring positive and free moving action of the operating member.

When the circuit breaker occupies its tripped position shown in Figure 2, the end 61 of the operating member 55 is engageable by a wiping action with a cam surface 70 on the trigger 30 to actuate the latter in resetting the circuit breaker as will be fully described later in the operation of the invention. It will also be noted that the trip member 25 is interposed between a stationary magnet 71 and a movable magnet 72 pivoted at 13 in the base 10. The movable magnet is attracted to the stationary magnet by the magnetic force created at the time of a short circuit, so as to strike and actuate the trip member 25 in order to trip the circuit breaker magnetically in the event of such a short circuit or extreme overload.

The operation of the invention is as follows:

With the circuit breaker in its set position and the switch closed as shown in Figure 1, current will be free to flow through a branch circuit between the bus contact 22 and the terminal 21. It will be noted that although the movable contact 20 is being maintained in firm, positive engagement with the stationary contact 21 by the heavily loaded spring 32, which results in excessive friction at the point of engagement of the trigger nose 42 with the keeper shoulder 43 of the latch 40, that this friction is reduced to a negligible amount at the point of engagement of the latch toe 44 with the trip member 25. This favorable and practically frictionless latching feature is due to the introduction of a force reducing couple having a relatively short lever arm between the axis of the pivot pin 41 and the point of engagement of the trigger nose 42 with the adjacent keeper shoulder 43, and a relatively long lever arm between the axis of the pivot pin 41 and the point of engagement of the latch toe 44 with the trip member 25.

Thus, any sustained overload, will, by heating the bimetallic trip member 25, flex same with but negligible opposition from the heavy spring load-

ing of the contact arm 19, so as to disengage the latch toe 44 and instantly release the trigger 30 which is now free to move to the position shown in Figure 2 wherein it strikes the end 61 of the operating member 55. This movement of the trigger under the urging action of the spring 32 shifts the spring from one side of the axis of the pivot lugs 18 to the other, to thereby instantly move the contact arm 19 to the position shown in this figure and open the switch.

To reset the circuit breaker, the operating member 55 is moved from the position shown in Figure 2, for wiping coaction of its end 61 with the cam surface 70 of the trigger 30 in moving the trigger towards its latching position with respect to the keeper shoulder 43 of the latch 40. As the spring 46 has swung the latch 40 to the extreme position shown in Figure 2, the trigger nose 42 is free to pass behind the keeper shoulder 43. During the final portion of the latching movement of the trigger, it strikes the cross bar 48 as shown in Figure 3, and swings the latch to its set position. The flexible arm 45 of the now cooled trip member 25 has been restored to its normal position shown in Figure 1, and is sufficiently flexed by the wiping action of the latch 40 during its latching movement, to be re-engaged by the toe 44 of the latch so as to retain the latter in its set position shown in this figure.

As the trigger nose 42 is now behind the keeper shoulder 43, the circuit breaker is reset with the switch open. The circuit between the bus contact 22 and the terminal 21 is now reestablished by manually moving the operating member 55 to its extreme position shown in Figure 1, so as to cause the contact arm 19 to be moved thereby until the spring 32 passes over the axis of the pivot lugs 18 and restores the contact arm to its extreme position shown in this figure, wherein the movable contact 20 firmly engages the stationary contact 21 under the heavy pressure imposed thereon by the heavily loaded spring 32.

Should a short circuit occur, the magnetic force created thereby will cause the movable magnet 72 to be drawn towards the stationary magnet 71 and to thus strike the flexible arm 45 of the trip member 25 so as to move same to its releasing position with respect to the latch 40, thereby tripping the circuit breaker and opening the circuit as above described. The circuit breaker is reset by restoring the operating member 55 to its position shown in Figure 3 and until the latch 40 is again retained in its set position by the trip member. The operating member is then moved to its position shown in Figure 1 to again close the circuit.

From the foregoing description, it will be manifest that irrespective of the heavy pressure imposed by the spring 32 upon the contacts 20 and 21 to insure a minimum of electrical resistance therebetween, the latch 40 interposed between the trigger 30 and trip member 25 removes the high friction latching load from the trip member, so that the latter will respond with practically no opposition from the spring 32 by releasing the latch 40 within a preselected narrow range of temperatures, thus insuring tripping of the circuit breaker with great accuracy when subjected to a sustained overload, and enabling high precision calibration of the circuit breaker to be effected.

I claim:

1. A circuit breaker comprising: a base formed of electrical insulating material; a contact arm pivoted to said base and capable of being turned

through a limited arc with relation to said base to and from open and closed positions; a movable contact carried on a first end on said contact arm; a trigger on, and capable of being swung through a limited arc in relation to, said base, said trigger having a first latching nose on its free end; an overcenter tension spring having one end secured to said contact arm near said first end of said contact arm and having its other end secured to said trigger intermediate the ends thereof, said spring being so placed as to tend to hold said contact arm in both its open and closed positions; a stationary contact carried on said base in such a position as to be engaged by said movable contact when said contact arm is in its closed position; a latch pivoted on, and capable of a movement through a limited arc in relation to said base and having a keeper toe so placed on one end of said latch as to engage said first latching nose on said trigger and having a second latching nose on the other end thereof; a spring so placed as to turn said latch about the pivot of said latch in such a direction as to release said first latching nose from the restraint of said keeper toe; trip means including a trip member having one end secured to said base and a free end thereof having releasable engagement with said second latching nose; an operating handle pivoted on said base and capable of being swung in a limited arc with relation to said base to and from open and closed positions; a first projection formed on said handle and so placed that when said handle is moved to its open position, said projection moves said trigger into a position where the first latching nose of said trigger is engaged by the keeper toe of said latch and said first projection also moves said contact arm from its closed position toward its open position; a second projection formed on said handle and so placed that when said handle is moved from its open to its closed position it moves said contact arm from its open position toward said closed position; a stationary magnet secured to said base; a movable magnet pivoted to said base and so placed that it can be moved toward said fixed magnet and when so moved will release said second latching nose from said trip means; and an electrical conductor through which electric current flows to said contact arm, said conductor being so placed that it induces a magnetic flux in said stationary and movable magnets and causes the free end of said movable magnet to move toward said fixed magnet.

2. A circuit breaker comprising: a base formed of electrical insulating material; a contact arm pivoted to said base and capable of being turned through a limited arc with relation to said base to and from open and closed positions; a movable contact carried on a first end on said contact arm; a trigger on, and capable of being swung through a limited arc in relation to, said base, said trigger having a first latching nose on its free end; an overcenter tension spring having one end secured to said contact arm near said first end of said contact arm and having its other end secured to said trigger intermediate the ends thereof, said spring being so placed as to tend to hold said contact arm in both its open and closed positions; a stationary contact carried on said base in such a position as to be engaged by said movable contact when said contact arm is in its closed position; a latch pivoted on, and capable of a movement through a limited arc in relation to said base and having a keeper toe so placed on one end of said latch as to

engage said first latching nose on said trigger and having a second latching nose on the other end thereof; a spring so placed as to turn said latch about the pivot of said latch in such a direction as to release said first latching nose from the restraint of said keeper toe; trip means including a trip member having one end secured to said base and a free end thereof having releasable engagement with said second latching nose, said trip member consisting of a bimetallic strip through which passes the current passing through said stationary and movable contacts, said strip being so placed that when heated above a critical temperature its free end is released from contact with said second latching nose; an operating handle pivoted on said base and capable of being swung in a limited arc with relation to said base to and from open and closed positions; a first projection formed on said handle and so placed that when said handle is moved to its open position, said projection moves said trigger into a position where the first latching nose of said trigger is engaged by the keeper toe of said latch and said first projection also moves said contact arm from its closed position toward its open position; a second projection formed on said handle and so placed that when said handle is moved from its open to its closed position it moves said contact arm from its open position toward said closed position; a stationary magnet secured to said base; a movable magnet pivoted to said base and so placed that it can be moved toward said fixed magnet and when so moved will release said second latching nose from said trip means; and an electrical conductor through which electric current flows to said contact arm, said conductor being so placed that it induces a magnetic flux in said stationary and movable magnets and causes the free end of said movable magnet to move toward said fixed magnet.

3. A circuit breaker comprising: a base formed of electrical insulating material; a contact arm pivoted to said base and capable of being turned through a limited arc with relation to said base to and from open and closed positions; a movable contact carried on a first end on said contact arm; a trigger on, and capable of being swung through a limited arc in relation to, said base, said trigger having a first latching nose on its free end; an overcenter tension spring having one end secured to said contact arm near said first end of said contact arm and having its other end secured to said trigger intermediate the ends thereof, said spring being so placed as to tend to hold said contact arm in both its open and closed positions; a stationary contact carried on said base in such a position as to be engaged by said movable contact when said contact arm is in its closed position; a latch pivoted on, and capable of a movement through a limited arc in relation to said base and having a keeper toe so placed on one end of said latch as to engage said first latching nose on said trigger and having a second latching nose on the other end thereof; a spring so placed as to turn said latch about the pivot of said latch in such a direction as to release said first latching nose from the restraint of said keeper toe; trip means including a trip member having one end secured to said base and a free end thereof having releasable engagement with said second latching nose; an operating handle pivoted on said base and capable of being swung in a limited arc with relation to said base to and from open and closed

positions; a first projection formed on said handle and so placed that when said handle is moved to its open position, said projection moves said trigger into a position where the first latching nose of said trigger is engaged by the keeper toe of said latch and said first projection also moves said contact arm from its closed position toward its open position; and a second projection formed on said handle and so placed that when said handle is moved from its open to its closed position it moves said contact arm from its open position toward said closed position.
